UNITED STATES PATENT OFFICE.

CHARLES SPAHMER, OF PHILADELPHIA, PENNSYLVANIA, ASSIGNOR TO
EUGENE PROMIS, OF SAME PLACE.

SCRAPER FOR BOOTS OR SHOES.

SPECIFICATION forming part of Letters Patent No. 444,716, dated January 13, 1891.

Application filed May 6, 1890. Serial No. 350,847. (No model.)

To all whom it may concern:

Be it known that I, CHARLES SPAHMER, a citizen of the United States, residing in the city and county of Philadelphia, in the State of Pennsylvania, have invented certain new and useful Improvements in Scrapers for Boots or Shoes, of which the following is a specification, reference being had to the accompanying drawings, forming part thereof.

10 My invention relates to that class of scrapers employed to remove dirt from the heels and soles of boots or shoes by the passing of the latter in frictional contact with the blade of the former, and has for its object the provision of a scraper that will be of simple, cheap, and durable construction, easily cleaned, and one that may be set flush with the pavement, step, floor, or its other location; and it consists of a suitable frame or receptacle of any desired size and configuration of outline, either with or without a bottom, that may be permanently or removably set with regard to the pavement, &c.; further, of a scraper or blade which is pivotally supported and adapted to be upset either into or out of position for use by means of a movement of the foot of the operator applied to a lug, or what I term an "upset," located on the face or upper side of the blade, and, further, 25 of a counter-balance or weight located on the back or under side of the blade to facilitate said operation; and to such end it consists of the construction, combination, and arrangement of parts hereinafter particularly described and claimed.

30 In the drawings, Figure 1 is a perspective view of a scraper constructed in accordance with my invention, the blade occupying a horizontal position and serving as a cover to its receptacle, such being its position when out of use as a scraper *per se*. Fig. 2 is a horizontal sectional view of the same, taken on the line *xx*, but represented as countersunk into a pavement or the like; and Fig. 3 35 is an end sectional view taken on the line *yy*, Fig. 2, and represents in full lines the blade when in its horizontal position out of use as a scraper *per se*, and in dotted lines showing the blade when in its vertical position and in

use as a scraper and a shoe applied thereto 50 in the act of being scraped.

Referring to the drawings, A is a suitable frame, box, or other receptacle, preferably constructed of iron, in a rectangular form; or it may be simply a recess or countersink in a 55 pavement, &c.

a are flanges or offsets formed on the inner side of the receptacle at one side near the top edge, which act as a seat for the blade B when the latter is in a horizontal position and out 60 of use as a scraper *per se*. The blade B when out of use acts as a lid or cover to the receptacle, and should be of size to snugly fit within the same. This blade is provided at opposite ends on its under side with downwardly-projecting lugs *b b*, and is pivotally connected to said receptacle by pivots *b' b'*, passing through said lugs and extending into the sides of the receptacle.

C is what I term the "upset," it being a lug 70 or other projection, preferably cast with the blade on its face or upper side at or about its center, and by means of which and the foot of the operator the blade can readily be upset out of a horizontal position into a vertical 75 position for use, and then acts as a prop or support for the blade when the latter is in use and takes up most of the strain from the rivets.

a' is a recess or depression in the rim of the 80 frame or receptacle and forms a seat to receive the upset C when the blade is in a vertical position, giving stability to the parts.

D is a counter-balance or weight, preferably 85 formed with the blade on its back or under side across its center, as shown, and is preferably a casting with a swell at one end, and tends to facilitate an easy upsetting of the blade into a vertical position for use.

To bring the blade into position for use it 90 is only necessary for the operator to press the toe of the boot on the upset C, when the blade will at once turn on its pivots and assume a vertical position. The upset C will then seat itself in the recess *a'* or depression in the rim 95 or edge of the receptacle and prop or support the blade. The heels and soles of the boot of the operator can then be scraped on the blade

in the usual manner, the dirt therefrom falling into the receptacle, after which operation a slight push with the toe of the boot against the blade will upset the blade and cause it to 5 resume its horizontal position.

If the receptacle be a box, it can be removed and inverted to discharge its contents, and if only a frame is used in conjunction with a countersink or space in the pavement, 10 floor, &c., it may be lifted out and the space cleaned, and if the construction and arrangement be a permanent one ample room is afforded for the removing of the accumulation when the blade is in a vertical position.

15 Having now fully described my invention, I wish it to be understood that I do not limit myself to the precise construction and arrangement of devices as shown in my drawings, but may vary the same in any manner 20 to better carry out the principle of my invention without departing from the true scope thereof.

I claim—

1. A scraper for boots or shoes, consisting 25 of a blade adapted to be pivotally and hori-

zontally supported over a space or receptacle and provided with a lug or upset on its face, whereby upon applied pressure thereto the blade may be caused to assume a vertical position for use and be supported in such position by said upset, as described, and for the purposes set forth. 30

2. A scraper for boots or shoes consisting of a blade adapted to be pivotally and horizontally supported over a space or receptacle 35 and provided with a lug or upset on its face, whereby upon applied pressure thereto the blade may be caused to assume a vertical position for use and be supported in such position by said upset, and a counter-balance or 40 weight on the back or underside of said blade to facilitate such upsetting, as described, and for the purposes set forth.

In testimony whereof I have hereunto signed my name this 24th day of April, A. D. 45 1890.

CHAS. SPAHMER.

In presence of—

WALTER ROBINSON,
JOHN JOLLEY, Jr.
